(57) **CLAIM**

The ornamental design for a hydraulic cylinder with free-floating pump and reservoir, as shown and described.

DESCRIPTION

This application also claims the priority of utility patent application 15/954,393, filed on Apr. 16, 2018, and currently pending.

FIG. 1 is a front elevational view of a hydraulic cylinder free-floating pump and reservoir showing the new design; FIG. 2 is a rear elevational view thereof; FIG. 3 is a right side elevational view thereof; FIG. 4 is a left side elevational view thereof; FIG. 5 is a top plan view thereof; FIG. 6 is a bottom plan view thereof; and, FIG. 7 is a left and front perspective view thereof.
